CLAIM

The ornamental design for a display screen with icon or packaging with surface ornamentation, as shown and described.

DESCRIPTION

FIG. 1 is a front view of a first embodiment of a display screen with icon or packaging with surface ornamentation; and,

FIG. 2 is a front view of a second embodiment of a display screen with icon or packaging with surface ornamentation. The broken lines are included for the purpose of illustrating a display screen or packaging and form no part of the claimed design.

1 Claim, 1 Drawing Sheet
